CLAIM

The ornamental design for a portable electronic terminal, as shown and described.

DESCRIPTION

FIG. 1 is a perspective view of an embodiment of a portable electronic terminal showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view illustrating a state where a circular portion of the portable electronic terminal of FIG. 1 is separated from a remaining portion of the portable electronic terminal;

The broken lines shown in the drawings depict portions of the portable electronic terminal. The dot-dash lines shown in the drawings depict the bounds of the claim. The broken lines form no part of the claimed design.

Our design is characterized by a watch strap that is continuously and naturally formed to encircle and hold a watch case or housing.
